United States Patent Office

Des. 198,130
Patented May 5, 1964

198,130

ELECTRICAL OUTLET

Le Roy F. Radtke, Chicago, Ill., assignor to Ideal Industries, Inc., Sycamore, Ill., a corporation of Delaware

Filed Feb. 4, 1963, Ser. No. 73,415

Term of patent 14 years

(Cl. D26—1)

FIG. 1.

FIG. 2.

FIG. 3.

FIG. 4.

FIG. 5.

FIGURE 1 is a front elevational view of an electrical outlet, showing my new design;
FIGURE 2 is a right end elevational view thereof;
FIGURE 3 is a rear elevational view thereof;
FIGURE 4 is a top plan view thereof; and
FIGURE 5 is a bottom plan view thereof.

I claim:

The ornamental design for an electrical outlet, as shown.
